[57] CLAIM

The ornamental design of a trailable skateboard ramp,
as shown and described.

DESCRIPTION

FIG. 1 is a perspective view of a trailable skateboard
ramp, showing my new design.

FIG. 2 is a top plan view of the erected trailable skate-
board ramp.

FIG. 3 is an end view of the erected trailable skate-
board ramp.

FIG. 4 is an end view of the trailable skateboard ramp
in the transporting position.
